(57) **CLAIM**

The ornamental design for a pastry with donut-shaped confetti, as shown and described.

DESCRIPTION

FIG. 1 is a top plan view of a pastry with donut-shaped confetti showing my new design,

FIG. 2 is a side elevational view thereof;

FIG. 3 is a top plan view of a second embodiment of a pastry with donut-shaped confetti showing my new design; and,
FIG. 4 is a side elevational view thereof.

The broken lines which define the bounds of the claimed design form no part thereof.
